UNITED STATES PATENT OFFICE.

WILLIAM G. CHILLIS, OF KLOTZVILLE, LOUISIANA, ASSIGNOR OF ONE-THIRD TO
NICK NOTO, OF KLOTZVILLE, LOUISIANA.

SPARK-ARRESTER.

1,090,026.

Specification of Letters Patent. Patented Mar. 10, 1914.

Application filed October 16, 1913. Serial No. 795,545.

To all whom it may concern:

Be it known that I, WILLIAM G. CHILLIS, a citizen of the United States, residing at Klotzville, in the parish of Assumption, State of Louisiana, have invented certain new and useful Improvements in Spark- Arresters; and I do hereby declare the following to be a full, clear, and exact description of the invention, such as will enable others skilled in the art to which it appertains to make and use the same.

This invention relates to new and useful improvements in spark arresters for smoke stacks and finds its particular adaptation when applied to the smoke stacks of locomotives.

The object of the invention resides in the provision of a device which may be readily attached to or detached from the smoke stack of a locomotive and which when in attached position effectually prevents the escape of sparks and cinders from the mouth of the stack.

A further object of the invention resides in the provision of such a device which is durable and efficient in use and which comprises a minimum number of parts so that it may be manufactured at a comparatively low cost.

With these and other objects in view, the invention resides in the novel combination, formation and arrangement of parts to be more fully hereinafter described and illustrated in the accompanying drawings and particularly pointed out in the claims here- to appended.

Reference is had to the accompanying drawings wherein similar characters of reference designate corresponding parts throughout the several views, and in which:

Figure 1 is a side elevational view of the improved spark arrester applied to the smoke stack of a locomotive, Fig. 2 is a top plan view of what is shown in Fig. 1, Fig. 3 is a central vertical sectional view of the spark arrester, and Fig. 4 is a perspective view of the cap member.

Referring now more particularly to the drawings, 5 designates the smoke stack of a locomotive having at its upper end the usual bead 6. The body member of the spark arrester comprises a frusto-conical portion 7 from the base of which extends a vertically disposed annular flange 8 fitting within the mouth of the stack and terminat-

ing in a horizontal annular flange 9 resting on the bead of the stack and extending outwardly thereof. This body member is secured to the stack by means of hook bolts 10 having their bills engaging the bead 6 and having their shank portions passed through the flange 9 and held by nuts 11 threaded on the said shanks.

For directing the sparks back toward the lower portion of the stack, a dome 12 is provided. The dome has lateral arms 13 extending horizontally from its edge and secured at their outer ends to an annular band 14 of the same size as the flange 9 and adapted to rest thereon. The dome, arms 70 and band may be formed integrally and the diameter of the base of the dome is slightly larger than the diameter of the apex of the frusto-conical body portion, it being observed that in this connection that the 75 body portion is inverted so that its sides serve to direct the sparks which may engage it downwardly. Escape of sparks from between the dome and the base member is prevented by a foraminous annular member 15 having its outer peripheral portion disposed between the band 14 and flange 9 and clamped by the bolts 16 securing said band and flange together. The inner peripheral portion of the member 15 is secured by the 80 bolts 17 to the inner surface of the dome.

From the foregoing it is seen that the sparks moving upwardly with the gases through the stack will engage the dome and be directed downwardly. Those sparks 90 which pass outwardly of the dome will engage the foraminous member 15 and will fall against the sides of the frusto-conical body portion 7, from thence sliding into the stack. It is observed that the sparks thus 95 all pass back into the stack and that the spark arrester does not become clogged.

What is claimed is:

1. A spark arrester comprising the combination with a smoke stack, of an inverted 100 frusto-conical member disposed therein and secured thereto, a dome provided at its base with horizontal arms for securing it to the frusto-conical member and an annular foraminous member secured to the base of 105 the dome and to the base of the frusto-conical member.

2. A spark arrester comprising the combination with a smoke stack, of an inverted 110 frusto-conical member having an annular

flange on its base resting on and secured to the stack, a dome having its base slightly larger in diameter than the apex of the frusto-conical member, horizontal arms extending from the dome and secured at their outer ends to an annular band, said annular band being disposed on and secured to the said annular flange and a foraminous annular member secured between the flange

and band and secured to the base of the 10 dome.

In testimony whereof, I affix my signature, in the presence of two witnesses.

WILLIAM G. CHILLIS.
